(57) **CLAIM**

The ornamental design for a LED lamp, as shown and described.

DESCRIPTION

FIG. 1 is a perspective view of a LED lamp showing our new design;

FIG. 2 is a front elevational view thereof, the rear side being a mirror image;

FIG. 3 is a left side elevational view thereof;

FIG. 4 is a right side elevational view thereof;

FIG. 5 is a top plan view thereof;

FIG. 6 is a bottom plan view thereof;

FIG. 7 is a reference view similar to FIG. 1, showing the claimed design portion disassembled from unclaimed subject matter for the purpose of illustrating the environment in which the article embodying the design is used; and, FIG. 8 is an additional reference view including enlarged partial view of interior details of FIG. 1 and FIG. 7.

The broken lines shown in the drawings illustrate portions of the LED lamp that form no part of the claimed design.
